(57) **CLAIM**

The ornamental design for a trellis wire clip, as shown and described.

DESCRIPTION

FIG. 1 is a front left top perspective view of a trellis wire clip showing our new design;

FIG. 2 is a rear right bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The dashed broken lines shown in the Figures represent portions of the trellis wire clip that form no part of the claimed design. The dot-dash broken lines define the bounds of the claimed design and form no part thereof.
